UNITED STATES PATENT OFFICE

GEORGE B. MASSEY, OF CHICAGO, ILLINOIS

TOWER EXCAVATOR

Application filed November 5, 1930. Serial No. 493,578.

This invention relates to excavators of the class in which a drag bucket is operated between spaced towers which, when in use, for example in levee construction work, are shiftable along parallel lines. The bucket is filled as it is dragged toward the head tower and is returned empty and above the ground toward the tail tower.

The objects of this invention are to provide improvements in the bucket suspension means and particularly with reference to the return of the bucket to the starting position after each digging operation. The purposes of the improvements are to rapidly return the bucket to the starting position while avoiding the use of a back-haul cable and breakages thereof; and to decrease the number of winding drums generally required in tower excavators.

The objects of the invention are accomplished by a construction as shown in the drawings, in which:

Figure 1 is a diagrammatic side view of a tower excavator provided with the present improvements and shows a section of a levee and a borrow pit from which the levee building material is taken.

Fig. 2 is a plan view of the tower excavator equipment shown in Figure 1.

Fig. 3 is a fragmentary detail view taken on the line 3—3 of Figure 1.

Fig. 4 is an enlarged perspective view of a drag bucket and its supporting means.

Tower excavators generally comprise a head tower and a tail tower which may be spaced apart some 500 or 600 feet with a cable extended between the towers from which a drag bucket is suspended. As the work progresses, the towers under their own power are shifted along parallel lines and for this purpose are frequently provided with the crawler type of propulsion means. The main cable extending between the towers serves as a track for a trolley from which the bucket is suspended. This cable passes over a sheave near the top of the mast of the main tower and runs down to a winding drum which is operated as required to allow slack in the cable so that the teeth of the bucket may engage the ground during the filling operation, at the end of which time slack is

taken out of the track cable sufficiently to permit the bucket to empty on the levee and then to run back above the ground toward the starting position, due to the winding up of the haul-back line, as assisted by gravity. When the bucket has reached the starting point for the digging stroke the track cable is again slackened, and the bucket is drawn along the ground toward the head tower by the drag line.

It is found in the use of such equipment that during the return motion of the bucket under the back-haul line, this line has a tendency to whip and break. The improved construction avoids the use of a back-haul line and its wind-up drum by the provision of a pair of diverging track cables which may be wound upon the same drum. These cables pass over widely spaced sheaves near the top of the main tower, and then converge toward the supporting trolleys for the bucket, and from there run substantially parallel to the sheaves or anchoring means on the tail tower.

When there is slack in the track cables, as is the case during the digging stroke, the drag line may freely pull the bucket along the pair of cables without much change in resistance due to the change in the angle of divergence of the track cables, between the bucket and the main tower as the bucket moves toward the main tower. At the end of the stroke, as the bucket is dragged toward the top of the levee, the track cables are drawn to a more taut position which causes the rear end of the bucket to be lifted, and the bucket empties. The further tensioning of the track cables and gravity causes the bucket to run back along the cables to its digging point. The tension on these diverging lines passing through the horizontally spaced trolleys from which the bucket is suspended, forces the bucket backwardly along the parallel portions of the track cable toward the start of its digging path. This general arrangement may be modified by having one only of these cables serve as a supporting track for the bucket and the other cable utilized mainly for forcing the bucket backward. In either case a quick return is effected by tensioning the cables.

The tower excavator equipment, shown in the drawings, varies from the customary arrangement mainly in having a pair of diverging track cables 1, rather than the single track cable usually employed. The improved construction also dispenses with the haul-back line for the bucket, including the necessary sheaves on the tail and head towers and the winding drum therefor.

Such parts of the construction illustrated, as are now well known in this art, include a head tower 2 and a tail tower 3, each generally provided with propulsion means so that they may be shifted as required along the line of work. The head tower is equipped with power driven wind-up drums 4 and 5 which are controlled from an operator's cage 6 carried by the mast 7 in position where the operator may view the action of a bucket 8. This bucket, in operation, is drawn toward the tower 2 by a drag line 9 passing over sheave 10 on mast 7 and from thence to the wind-up drum 4.

The new parts of the equipment are the two track cables 1 which, at the tail tower, are either anchored thereto or led from a wind-up drum 11 over sheaves 12 which are close together on tower 3 and from these sheaves lead to horizontally spaced and more widely spaced sheaves 13 carried by a crosstree 14 secured to the upper end of mast 7. The track cables 1 lead from the sheaves 13 to a single wind-up drum 5.

The drag bucket 8 is of well-known construction and is supported at its rear end by cables 15 from which it is suspended from a trolley 16, arranged to run along the track cables 1. It is customary to use but a single trolley and a single track cable.

The chains 15 are connected by a bar 17 near the trolley 16. The trolleys are spaced apart substantially the same as the spacing of sheaves 12 on tower 3. The track cables extend parallel from tower 3 to trolleys 16 which serve to hold the track cables together at the point of the trolleys wherever the bucket may be along the track cables. From the trolleys the track cables diverge to the horizontally spaced sheaves 13 on the head tower 2.

In the operation of this equipment, in the filling of the bucket, the latter is drawn from a position near the tail tower toward the head tower by the drag line 9, as the latter is wound upon rotating drum 4. During the filling operation, sufficient slack is permitted in track cables 1 to allow for the required engagement of the teeth of the bucket with the bottom of the borrow pit 18. The bucket is drawn over the ground while filling and transporting the load up the levee to the desired place for dumping, when the hauling on the drag line is stopped and the track cables are pulled up, thus raising the rear end of the bucket and emptying it. The bucket is

shown in such position by the broken lines in Fig. 1.

In order to cause the bucket to return to its starting position more rapidly than by gravity alone, the track cables 1 are tensioned by a further rotation of winding drum 5. This tensioning of the track cables, which diverge from the trolley 16 to the sheaves 13, forces the trolleys and the bucket suspended therefrom to run backwardly along the track cables to the starting position. With this arrangement of diverging track cables, a back-haul line is unnecessary. The back-haul line generally runs from the rear end of the bucket to a sheave on the tail tower and from thence to a sheave on the head tower to a winding drum on the latter. In order to return the bucket to the starting position as rapidly as possible, it is customary to rotate the back-haul winding drum at a comparatively high rate of speed, such as to cause whipping of the back-haul line and occasional breakage thereof.

Such an arrangement is now dispensed with, as the bucket may be more rapidly returned and with less breakage by the spreading action on trolley 16 when the diverging track cables 1 are tensioned.

Although but one specific embodiment of this invention is herein shown and described, details thereof may be modified without departing from the claims.

I claim:

1. In a tower excavator, head and tail towers, a pair of horizontally spaced track cables extending between said towers, supporting means on the head and tail towers for the track cables, said supporting means being more widely spaced on the head tower than on the tail tower, a pair of trolleys arranged to run upon said track cables, a drag bucket suspended from said trolleys, a drag line attached to the drag bucket and extending to winding means on the head tower, and means on one of said towers for simultaneously tensioning the track cables.

2. In a tower excavator, head and tail towers, a pair of horizontally spaced track cables extending between said towers, supporting means on the head and tail towers for the track cables, said supporting means being more widely spaced on the head tower than on the tail tower, a pair of trolleys arranged to run upon said track cables, a drag bucket suspended from said trolleys, a drag line attached to the drag bucket and extending to winding means on the head tower, and means on the head tower for simultaneously tensioning or slackening the track cables.

3. In a tower excavator, head and tail towers, a combined track cable and bucket return equipment comprising a pair of cables extended between said towers, a drag bucket, trolleys for running on said cables and from which the bucket is suspended, said cables

being substantially parallel from the trolleys to the tail tower, and diverging from the trolleys to separate sheaves on the head tower.

4. In a tower excavator, head and tail towers, a combined track cable and bucket return equipment comprising a pair of cables extended between said towers, a drag bucket, trolleys for running on said cables and from which the bucket is suspended, said cables being substantially parallel from the trolleys to the tail tower, and diverging from the trolleys to separate sheaves on the head tower, said sheaves being spaced apart horizontally to provide a greater horizontal distance between the same to the distance between the trolleys for supporting the bucket.

Signed at Chicago this first day of November, 1930.

GEORGE B. MASSEY.
